JOSEPH D. RAMSEY, OF DORCHESTER, MASSACHUSETTS

VALVE

Application filed August 16, 1929. Serial No. 386,373.

The present invention relates to valves, and more particularly to a novel and improved valve particularly adapted for use in connection with water faucets or similar installations.

An important object of the present invention is the provision of a valve comprising an outer casing having a plurality of discharge openings or ports therein, each of said 10 ports leading to a nozzle, and an inner valve casing or portion having a single discharge port or opening therein, whereby partial turning of the outer valve casing will permit a flow of water through a predetermined discharge port in the outer casing, or a stoppage 15 of said flow.

Another feature of the invention is the provision of adjustable means to regulate and determine the extent of turning movement desired.

A further object of the invention resides in the provision of novel means to permit a gradual turning on and shutting off of the water flow through a desired port. To accomplish this last mentioned desirable result, I incline the ports in the outer valve casing angularly with respect to the single port in the inner fixed valve casing. Thus, when a port in the outer valve casing is 20 brought into register with the port in the inner valve casing, there will be a gradual flow of the water into said outer casing port, because of its angular position. This will 25 eliminate the objectionable pounding common in water valves. Conversely, when the flow of water is shut off from said discharge port, such stoppage will be gradual instead of abrupt.

40 A further object of the invention resides in the provision of means associated with one of said discharge ports to act as a sediment collector to prevent the passage of sediment through a certain one of said nozzles, 45 and means associated with another of said

discharge ports to act as flushing means to clear the inner casing of said sediment.

The above and other features and objects of the invention, details of construction, combinations of parts, and advantages, will be 50 hereinafter more fully pointed out, described and claimed.

Referring to the drawings, illustrating a preferred embodiment of the invention,

Fig. 1 is an exterior view of the valve as 55 applied to a free flowing and a filtering nozzle, the latter and the filtering apparatus being shown in section;

Fig. 2 is a cross-sectional view on the line 2—2 of Fig. 1;

Fig. 3 is a vertical sectional view of the 60 fixed and rotatable valve casings or portions;

Fig. 4 is a view, partly in section, through the ports in the fixed and rotatable valve casings, showing the inner port registering with 65 one discharge port and the other discharge port in inoperative position;

Fig. 5 is a sectional view similar to Fig. 4 illustrating both discharge ports in inoperative or closed position;

Fig. 6 is a vertical sectional view on the line 6—6 of Fig. 5; and

Fig. 7 is a sectional detail illustrating a port in the rotatable casing coming into register with the port in the fixed casing.

Referring now to the drawings, for a particular description of the invention, my novel valve may be applied to an ordinary faucet, which of course has a separate turning plug therein, or may be, and preferably is, as 80 shown, threaded directly onto a supply pipe 1 having a reduced threaded portion 2 upon which the upper part of my novel valve 3 is fitted by a correspondingly internal threaded section 4, the upper portion of said valve 85 being formed as a nut to enable a tight union to be obtained between the threaded portions 2 and 4. The valve 3 comprises a fixed internal member or casing of the valve, having a downwardly extending portion 5 having a 90

- cored recess 6 therein, through which portion 5 a port 7 is provided. The turning or rotatable portion of the valve comprises the outer member 8 carrying a nozzle 9 on one side, and a second and upwardly extending nozzle 10 approximately 90° apart. Opening from the rear of the nozzle 9 is a port 11 adapted to register with the discharge port 7 in the fixed member 5, when these two ports are brought into alignment by the rotation of the outer casing 8. A port 12, at the rear of the nozzle 10, is provided in the casing 8 to register with the port 7, when said two ports 12 and 7 are brought into alignment. Rotative movement of the nozzle carrying casing 8 serves to either shut off the central port entirely, preferably when moved as illustrated in Figs. 5 and 6, with said port 7 positioned between the ports 11 and 12, or by slight turning movement or rotation in either direction to register or align the port 7 with either of the ports 11 or 12 desired.
- In the particular combination of free flowing and filtering nozzles illustrated in Fig. 1, wherein a filtering device is applied to the nozzle 10, I prefer to form the port 12 opening into the nozzle 10 of reduced area so as to prevent undue stress and volume from reaching the filtration apparatus 13.
- Preferably, also, I form the port 12, as best illustrated in Fig. 7, inclined, or with slanting walls, so that the admission of water thereto from the port 7 is gradual when being turned into open position. Similarly, in turning the casing 8 to shut off a flow of water from the nozzle 10, the turning off action will be gradual and not sudden or abrupt. Such gradual supply and shut-off, prevents undue pressure in the piping, and strain, "pounding", and the like, due to the sudden stopping or starting of the current flow. I preferably also form the port 11 inclined relatively to the port 7, similar to the port 12, with the exception that the port 11 is of greater area than the port 12, as shown in the structure of the drawings.
- In order to more effectually control the turning movement or rotation of the casing 8 and especially to limit its rotation to just the right position for the nozzle 10, I provide an automatic stop, comprising a boss 14 formed on the upper part 3 of the fixed valve member, and a collar 15, which may be clamped about the nozzle 10 in any desired position, said collar having one arm extending sufficiently, as shown in Fig. 2, to engage the stop 14. I preferably form the collar 15 also as a clamp, having the longer arm 16 of sufficient length to strike against the boss 14, as just explained, with a shorter arm 17 united thereto by a screw 18 to clamp the collar firmly upon the nozzle 10 and at proper height and position to accurately register or align the ports 7 and 12. This feature is most important, insuring quick and

accurate adjustment of the supply of water admitted to the filter, regardless of the amount going through the free flow passage. I also prefer to tap through the boss 14 to receive a set screw 19 which will further serve to hold the valve upon the pipe 1 carrying it, and prevent the displacement of the valve through constant swinging of the casing 8 and the nozzles carried thereby.

As illustrated in Fig. 3, I form the two members 5 and 8 of slightly wedge shaped contour, in order to insure a snug, water-tight fit, while still permitting rotation of one upon the other. To hold the two members 5 and 8 in assembled position, I provide a central depending stud 20 on the lowermost portion of the fixed valve member 5, which stud has a reduced portion threaded to receive a nut 21. A washer 22 fitted over the stud 20 and of appropriate diameter to bear against the lower rim of the outer or turning casing 8 (see Fig. 3) enables the two members, 5 and 8, to be held firmly in position, adjustment of the nut 21 acting to tighten said members to a water-tight contact. To further insure water-tightness of the valve, as well as to provide a lubricant therefor, I leave a recess between the uppermost rim of the outer casing 8 and a shoulder 23 in the fixed portion 5, filling said recess with any suitable lubricating packing 24, and fitting a band or ring 25 thereover to provide a neat appearance and to retain the packing in position. The ring 25 is wedged over a reduced part of the fixed member 3 and overlaps the edge of the rotatable casing 8, sufficient space being provided between the shoulder 23 and member 8 to permit tightening of the nut 21 from time to time to compensate for wear. A washer 26 is also fitted on an internal shoulder 27 in the upper portion 3 to make a water-tight joint between the complementary threaded sections 2 and 4.

Another important feature of my valve, especially desirable when used in connection with a filter on one nozzle, is the provision of my novel sediment collecting means for the filter carrying nozzle, and cooperating sediment flushing means for the free flowing nozzle.

My preferred construction for carrying out this feature consists in forming the port 12 in the filter carrying nozzle 10 so as to receive the flow of water from the upper portion of the recess or valve chamber 6, which port also is of reduced area to cut down the flow of water therethrough, forming a regulated flow through the recess 6, thus further permitting sediment to settle therein. The settling of said sediment is further increased by the gooseneck arrangement or shape of the nozzle 10. By having the port 12 of less depth than the port 7 a wall 28 is formed, constituting a sediment collecting pocket in the bottom of the recess 6 approximately below the dotted

line 29. When the casing 8 is turned to open the free flowing port 11, which port has a depth equal to that of the port 7, the sediment collected below the dotted line 29 is at once 5 washed out, aided by the increased volume and flow permitted by the larger port 11. Thus a filtering valve together with an automatic cleaning of said valve is produced which I believe to be a distinct novelty in this 10 art, and therefore I claim the same broadly in the present application.

As the flow of water through a filter is relatively slow at all times, the reduction in the supply to the filter renders no inconvenience 15 in the service and greatly prolongs the life and usefulness of the filter itself. The arrangement of the sediment collecting pocket in connection with the filter nozzle furthermore greatly aids in keeping the filter pack- 20 ing clean, irrespective as to whether or not my improved type of filter is used or other water filters.

The operation of my valve will be readily understood. With the fixed portion threaded 25 onto piping and the outer casing fitted thereon, the adjustable collar 15 is applied to the nozzle 10 in position, both rotatively with regard to said nozzle, and at appropriate height to limit the turning movement of the 30 nozzles with the port 12 in open engagement, as shown in Fig. 4. A slight movement to the right, viewing Fig. 4, acts to shut off the liquid supplied to the nozzle 10 and close the valve, as shown in Fig. 5. Further move- 35 ment to the right of the casing 8 brings the free flowing nozzle 9 in position with its port 11 to register with the port 7 of the fixed valve member 5. It is unnecessary to have a stop to limit the turning movement of this nozzle, 40 as the amount of liquid flow is readily determined by the extent to which the ports 11 and 7 are brought into register, this being preferably under control of the operator, and can well be regulated by the extent of open- 45 ing of the usual faucet or bib handle.

It will be appreciated that either of the nozzles 9 or 10 may be utilized as the handle or means for rotating or operating the valve. It will also be appreciated that by having the 50 nozzle 10 of appropriate form and height to receive the filter 13, either nozzle may be swung into position over a pitcher or other receptacle, both the discharge openings of the free flowing nozzle 9 and filter 13 being 55 on the same horizontal plane, that is, of equal elevation. With the nozzle 10 in position to receive the water flow from the port 7, the sediment collecting recess and reduced flow through the valve, coupled with the 60 gooseneck construction of the nozzle 10, causes a preliminary filtration of the water directly in the valve itself, any sediment tending to settle in the pocket caused by the wall 28. Any such sediment is, of course, 65 quickly flushed or swept out when the in-

creased volume and flow is permitted through the nozzle 9, with its port 11 opening substantially into the bottom of the recess 6 and eliminating the sediment collecting pocket.

Furthermore, my arrangement, whereby 70 the filter is in a raised position affording ample height or clearance under the regular faucet nozzle so that a pitcher or other container, when positioned under the faucet, can receive either filtered water or the regular 75 free flow of water from the faucet with full and equal clearance afforded by the position of the faucet for both, is a most important feature. Thus in my invention, I provide a plurality of nozzles, with one or more (preferably 80 the filter-carrying nozzle) turned upwardly as a gooseneck which is a distinct novelty and which I claim herein broadly.

While I have necessarily described my present invention somewhat in detail, it will 85 be appreciated that I may vary the size, shape and arrangement of parts within reasonably wide limits without departing from the spirit of the invention.

My invention is further described and de- 90 fined in the form of claims as follows:

1. A valve having an inner fixed portion, a rotatable outer portion, a plurality of delivery nozzles on said outer portions, rotation of said outer portion acting to turn on or 95 shut off the liquid flow through the nozzles, in combination with means cooperating with one nozzle to provide a sediment collecting pocket in the valve, and means co-operating with another nozzle to flush said 100 sediment collecting pocket.

2. A valve having an inner fixed portion, a rotatable outer portion, a plurality of delivery nozzles on said outer portion, rotation of said outer portion acting to turn on or 105 shut off the liquid flow through a predetermined nozzle, in combination with means co-operating with one nozzle to reduce automatically the liquid flow through said valve and to constitute a sediment collecting pocket 110 in the valve, and means co-operating with another nozzle to flush said sediment collecting pocket and afford an increased current flow through said valve.

3. A valve of the kind described, comprising a fixed inner portion having a port therein, and an outer portion having a plurality of ports therein, the ports in said outer portion being angularly disposed relative to the port in the fixed member, one of the ports in 120 said outer portion being of less depth area than the port in the fixed portion.

4. A valve of the kind described, comprising a fixed inner portion having a port therein, and an outer portion having a plurality of ports of varying sizes therein, one of the ports in the outer portion being of less depth than the port in the fixed portion, the ports in said 125 outer portion being angularly disposed relative to the port in the fixed portion.

5. A valve of the kind described, comprising a fixed inner portion having a port therein, and an outer portion having a plurality of ports of varying sizes therein, one of the ports in the outer portion being of less depth than the port in the fixed portion, the ports in said outer portion being angularly disposed relative to the port in the fixed portion, and said outer portion being rotatable to register a predetermined port therein with the port in the inner fixed portion.

In testimony whereof, I have signed my name to this specification.

JOSEPH D. RAMSEY.
